UNITED STATES PATENT OFFICE.

SIDNEY J. STAPLES, OF WEST NEW YORK, NEW JERSEY, ASSIGNOR TO THE AUTO PNEUMATIC ACTION COMPANY, A CORPORATION OF NEW YORK.

GEARING FOR OPERATING THE ROLLS FOR MUSIC-SHEETS.

1,159,287.

Specification of Letters Patent.

Patented Nov. 2, 1915.

Application filed November 26, 1913. Serial No. 803,323.

To all whom it may concern:

Be it known that I, SIDNEY J. STAPLES, a citizen of the United States, residing at West New York, in the county of Hudson 5 and State of New Jersey, have invented a new and useful Gearing for Operating the Rolls for Music-Sheets, of which the following is a specification.

The object of this invention is to provide 10 a new and improved gearing for operating the rolls for music sheets so that the same can be drawn over the tracker for playing and quickly rewound.

The principal object of the invention is 15 to provide a gearing of this nature which shall be easy to manufacture and efficient in operation.

The gearing is illustrated in the accompanying sheet of drawings in which,

20 Figure 1 is a front elevation partly in section of the same; Fig. 2 is a rear elevation with the parts in the opposite position from that shown in Fig. 1; Fig. 3 is a sectional plan view taken on the line 3—3 of Fig. 1; 25 Fig. 4 is a sectional elevation taken on the line 4—4 of Fig. 1; and Fig. 5 is a sectional elevation on the line 5—5 of Fig. 1.

Referring to the drawing and in detail, A designates the cheek or right-hand side 30 of the spool box. Secured to the same by suitable screws is a bracket 10. A shaft 11 is journaled in the base of the projecting part of said bracket. Said shaft has on its end the usual bushing 12 carrying a spring- 35 pressed tenon 13 for engagement into the socket or mortise formed in the right-hand end of the music spool B. A sprocket pinion 14 is secured on the end of said shaft projecting beyond the bracket. Secured in 40 the bracket by a nut is a stud or bolt 15 on which is journaled a cam 16 having a projecting arm 17. The cam 16 engages the end of the shaft 11 and the arm 17 is connected to the automatic shifting mechanism 45 in a manner well understood, so that the cam controls the axial position of the shaft 11 and adjusts the music spool B automatically in proper position so that the music sheet C will run properly on the 50 tracker T. The cam 16 and the arm 17 are connected together by a tie 18, the cam, tie and arm being preferably pressed out of one piece of sheet metal. Another bracket 55 19 is secured to the cheek A by suitable screws. Journaled in the hub in this bracket

fitting into the cheek is a shaft 20 which carries on its end a pinion 21. The shaft 20 is held in place in a bracket 19 by a collar 22 held by a suitable screw on the shaft. A power shaft 23 is journaled in a projecting 60 arm 190 of the bracket 19. The end of the shaft 20 is reduced and fits into a hole in the end of the power shaft so that the two shafts 20 and 23 will come in line and each will be free to turn independently of the 65 other. A collar or hub 24 is secured on the power shaft by a suitable screw. This hub has a projection or clutch tooth 25 arranged in position to engage with a projection or clutch tooth 26 formed on the collar 22. 70 The hub 24 is also provided at its outer end with a clutch tooth 27 set in position to engage a clutch tooth 28 formed on a sprocket gear 29 which is loosely mounted on a power shaft 23. The gear 29 has an extending hub 75 30 provided with a slot in which is fitted an arm 31 secured to the bracket by a screw, whereby the gear 29 will be held in place axially on the power shaft 23.

A sprocket chain 32 is led around the 80 sprocket gear 29 and the sprocket pinion 14. Adjustably secured by means of a nut and screw to the arm 31 is an arm 33 carrying a stud 34 on which is loosely journaled a roller 35 which engages the sprocket chain 32. By 85 adjusting the position of the arm 33 on the arm 31 the wrap of the sprocket chain on the sprocket gear 29 and the tightness of the sprocket chain can be adjusted.

A shifting lever 36 is pivoted by a suitable screw on the bracket 19. This lever has a pin or projection 37 which engages into a groove 38 formed in the hub 24. A light loop of wire 39 is adjustably secured to the lever 36 by a screw 40. The end of this loop carries a block and friction pad 41 which, when the lever is in the position shown in Fig. 1, comes in position to engage the side of the sprocket gear 29. A cam lever 42 is pivoted on a suitable screw 43 secured in 90 the foot of the bracket 19. This cam lever has two notches 420—421 which are engaged by a roller 44 journaled on a screw 45 secured in the end of the shifting lever 36. The journal 46 or pivot of the take-up spool 95 D is fitted into a hole bored centrally in the pinion 21, a small spiral spring being inserted in the hole to keep the take-up spool in its left-hand position.

A plate 48 is secured by screws to the in- 110

side of the cheek A. A screw stud 49 is secured in this plate and running on the same is an intermediate gear 50 which is in continuous mesh with the pinion 21. Journaled on the stud screw 49 is an arm 51 secured in the end of which is a screw stud 52 on which is loosely mounted a pinion 53. The screw stud 52 is extended through the arm 51 and is engaged by a projection 422 extending out from the cam lever 42. A spiral spring 54 is arranged between the screw stud 52 and a screw 55 secured in the cheek. A gear 56 is arranged on the take-up spool D.

15 The pinion 53 is in constant engagement with the intermediate gear 50 and is made wide-faced so that when in its lower position, as shown in Fig. 5, it will engage with the gear 56 on the take-up spool. It also 20 will be noted that when the arm 51 is raised to the position shown in dotted lines in Fig. 5, the pinion 53 will be lifted out of engagement with the gear 56 and the take-up spool D will be free to run backward.

25 The operation is as follows.—Power is applied from a suitable motor by any suitable connection such as the usual sprocket pinion, chain and gear, to operate the power shaft 23. The shifting lever 36 is connected by the usual link-work to the controlling lever of the instrument. When the shifting lever 36 is in the position shown in Fig. 1, the hub 24 will be in the left-hand position so that its clutch tooth 25 will engage with 30 the clutch tooth 26 on the collar 22, whereby power will be transmitted from the shaft 23 to the pinion 21. When the parts are in this position, the roller 44 will be in the notch 420 of the gear lever 42, which will bring 35 the pinion 53 to the position shown in Fig. 5, whereby power will be transmitted from pinion 21, gear 50, pinion 53 to the gear 56 on the take-up spool, whereby the latter will be rotated at a slow speed in a direction to 40 draw the music sheet forward over the tracker. As this action takes place, the music spool B will be rotated by the note-sheet and by means of the sprocket pinion 14, and sprocket chain 32, the sprocket gear 29 will be slowly rotated. When the parts 45 are in this position, the friction pad or block 29 will be slowly rotated. When the parts 50 are in this position, the friction pad or block 41 will engage the side of the sprocket gear 29 and thus will hold back slightly on the music spool so that there will be some tension 55 put on the music sheet as the same is drawn over the tracker.

60 The operation is reversed when the shifting lever 36 is thrown to the position shown in dotted lines in Fig. 1 and to the position shown in Fig. 2. When the lever is thrown to this position, the hub 24 is moved to the right so that the clutch tooth 27 will engage the clutch tooth 28 on the sprocket gear 29 and so that the clutch teeth 25 and 26 will 65 be disengaged. By this adjustment, the

power will be taken through the sprocket gear 29, sprocket chain 32, sprocket pinion 14, and the music spool will be quickly rotated in a reverse direction to rewind the music sheet. When this action takes place, 70 the friction pad 41 is disengaged from the side of the sprocket gear 29. Also when this action takes place, the roller 44 on the shifting lever 36 will come into the notch 421 of the cam lever 42. This will raise the 75 pinion 53 clear or out of mesh with the gear 56 on the take-up spool. This will allow the music spool to turn backward so that the music sheet can be drawn therefrom. When the parts are in this position, it will be noted 80 that the pinion 21, intermediate 50, and pinion 53 are not operated, whereby there is very little friction interposed to the rewinding of the music sheet.

85 The notches 420 and 421 insure the correct action of the shifting lever, the spring 54 acting to pull the notched end of the cam lever 42 upwardly so that the shifting lever 36 will have to assume one or the other of its two positions. By throwing the pinion 90 53 sidewise or down and up into and out of mesh with the gear 56, a very positive and accurate gear shift is obtained. By the use of the double clutch device, consisting of the hub 24 and its two clutch teeth, the gear- 95 ing above described is thrown out of operation for rewinding. The notched cam lever, as previously described, insures the accurate positioning of the shifting lever in either one of its two positions. The tension spring 100 54 operates to hold the pinion 53 accurately in mesh with the gear 56 when the parts are in the position shown in Fig. 5.

105 The spring and friction block 41, co-operating with the side of the sprocket gear 29, forms an efficient braking mechanism for the purpose set forth.

110 By the mechanism described, the functions necessary to a gearing of this kind are accurately performed.

115 The details and arrangements herein shown and described may be greatly varied by a skilled mechanic without departing from the scope of my invention as expressed in the claims.

Having thus fully described my invention, what I claim and desire to secure by Letters-Patent is,—

120 1. A gearing for driving take-up and music spools, consisting of an intermediate gear, a wide-faced pinion continuously meshing therewith, and movable in a curved path concentric with said gear, a gear on the take-up spool, and means for moving the wide-faced pinion in said path into and out of mesh therewith.

125 2. A gearing for driving take-up and music spools, consisting of a pinion arranged in line with the take-up spool, a stud or shaft carrying an intermediate gear mesh- 130

ing therewith, an arm pivoted on said stud or shaft and carrying a wide-faced pinion in continuous engagement with said intermediate gear, a gear on the take-up spool, and 5 means for swinging said arm about its pivot to throw said wide-faced pinion into and out of mesh with the gear on the take-up spool.

3. A gearing for driving take-up and music spools, consisting of a pinion arranged 10 in line with the take-up spool, a stud or shaft carrying an intermediate gear meshing therewith, an arm pivoted on said stud or shaft and carrying a wide-faced pinion in engagement with said intermediate gear, 15 a gear on the take-up spool, means for moving said arm to throw said wide-faced pinion into and out of mesh with the gear on the take-up spool, and a spring for holding the wide-faced pinion normally in engagement 20 with the gear on the take-up spool.

4. In a gearing for driving take-up and music spools, the combination of a power shaft, a driving pinion arranged in line therewith, a sprocket gear thereon connected 25 to rotate the music spool, a hub having clutch mechanism, means so that the hub can be thrown to operate either the pinion or the gear, an intermediate gear driven from said pinion, a wide-faced pinion driven 30 from said intermediate gear, a gear on the take-up spool, and connections arranged so that when the power shaft is connected to said pinion, the wide-faced pinion will be in mesh with the gear on the music spool, and 35 so that when the hub is connected to the sprocket wheel, the wide-faced pinion will be disengaged from the gear on the music spool.

5. In a gearing for driving take-up and 40 music spools, the combination of a driving shaft, a sprocket wheel connected to turn the music spool, a pinion, a hub having clutch teeth to connect with the sprocket wheel or with the pinion, a shifting lever 45 for moving the hub, an intermediate gear in mesh with the pinion, a wide-faced pinion in mesh with the intermediate gear, a gear on the take-up spool, and a cam lever actuated by the shifting lever for throwing the 50 wide-faced pinion into and out of mesh with the gear on the take-up spool.

6. In a gearing for driving take-up and

music spools, the combination of a driving shaft, a sprocket wheel connected to turn the music spool, a pinion, a hub having 55 clutch teeth to connect with the sprocket wheel or with the pinion, a shifting lever for moving the hub, an intermediate gear in mesh with the pinion, a wide-faced pinion in mesh with the intermediate gear, a gear 60 on the take-up spool, a cam lever having two notches actuated by the shifting lever for throwing the wide-faced pinion into and out of mesh with the gear on the take-up spool. 65

7. In a gearing for driving take-up and music spools, the combination of the power shaft, a sprocket wheel loosely arranged thereon and connected to turn the music roll, a hub, gearing to turn the take-up spool, 70 means for shifting the hub to operate the sprocket gear or said gearing, a shifting lever for operating said hub, a spring mounted on said lever and a friction pad carried by said spring and positioned for engagement 75 with the side of said sprocket wheel when the hub is connected to said gearing.

8. In a gearing for driving take-up and music spools, the combination of a power shaft, a second shaft arranged in line therewith, a series of gears between said second shaft and take-up spool for driving said spool, one of said gears being movable to render said gear drive operative or inoperative, and a clutch mechanism operative to 80 connect or disconnect said shafts. 85

9. In a gearing for driving take-up and music spools, the combination of a power shaft, a second shaft arranged in line therewith and fitted into the power shaft, gearing from the second shaft to the take-up spool, a sliding clutch mounted on the power shaft, clutch engaging means on the second shaft, and means for engaging the clutch and clutch engaging means so that the 90 power shaft will turn the take-up spool. 95

In testimony whereof I have hereunto set my hand, in the presence of two subscribing witnesses.

SIDNEY J. STAPLES.
